United States Patent Office.

ALBERT BOSCHKE, OF BOSTON, MASSACHUSETTS.

Letters Patent No. 82,376, dated September 22, 1868.

IMPROVED DREDGING-MACHINE.

The Schedule referred to in these Letters Patent and making part of the same.

TO ALL WHOM IT MAY CONCERN:

Be it known that I, ALBERT BOSCHKE, of Boston, in the county of Suffolk, and State of Massachusetts, have invented an Improvement in Dredging-Machines; and I do hereby declare that the following, taken in connection with the drawings which accompany and form part of this specification, is a description of my invention sufficient to enable those skilled in the art to practise it.

My improved dredging-machine is especially designed for operating on hard bottom, such as cannot well be removed by the ordinary dredging-machines employing only the well-known system of buckets or scoops moved by an endless chain.

It is also designed for operation in deep water, where dredging-machines employing a scoop or bucket alone, on the end of a lever, by which the said scoop or bucket is thrust against and into the bottom, and is then elevated, fail to act efficiently, by reason of the great amount of power lost or non-utilized, when, as in deep water, the lifting-chain forms an acute angle with the scoop-lever, so that more power is expended on the resisting fulcrum of the scoop-lever than is utilized in lifting the bucket with its load.

In all previous submarine excavators or dredging-machines, so far as I am informed, the implements by which the material of the bottom is loosened act intermittently, but in my invention the loosening-implement acts continuously, and the loosened material is elevated by a separate instrumentality.

In my invention, I make use of what may be termed a plow, inasmuch as it operates to loosen the earthy material of the bottom, which plow is peculiar, in that it is of a scoop or hood-form, having what may be called a back, sides, and bottom, between which boundaries the material which the plow loosens is received, and is confined till conveyed out of said boundaries by an elevator.

My invention consists in the combination of three elements or instrumentalities, a floating hull, a plow, and an elevator, when these are combined and arranged to operate together substantially as follows:

The hull, which is designed to contain efficient and powerful engines and boilers, has a scoop-plow, with sides, back, and bottom, which plow is so arranged that it may be adjusted to any distance from the bottom, within reasonable limits, and the elevator, which consists of a series of buckets borne upon an endless chain, has its upper bight pass over a roller made secure to the hull above water, while the lower bight passes over a roller pivoted in the sides of the plow, so that the elevator always conforms to changes in the position of the plow, and the buckets of elevator always, when in motion, enter between the boundaries of the plow, and remove the material which accumulates therein as the hull is drawn forward, carrying with it the plow.

The drawing shows, in sectional elevation, a dredging-machine embodying my invention, in which machine *a* denotes the lever-borne scoop-plow.

b b represent the buckets, which are mounted on an endless chain, *c*, which passes over rollers, one at each end of frame *d*, and others located in the frame between the end rollers.

The upper roller *e* and the lower roller *f* are polygonal, to suit the links of the chain, after the manner of sprocket-wheels, and the intermediate or supporting-rolls are cylindrical.

The movement of the chain-borne buckets is effected by power applied to the shaft *g*, on which the upper roller *e* is mounted, and the frame *d* swings as an arm on the axis of said shaft, so that the lower end of the frame can be made to assume any position desired, the shaft *g* being mounted in suitable bearings on the hull *h*, which is made with an opening through it, for the passage, and the elevation and depression of the dredging-machinery, and which has sufficient buoyancy to sustain the weight thereof, and the weight of the engines, boilers, fuel, &c.

The plow *a* is made with strong projections or teeth *i*, and with a hood, *j*, and is pivoted, by straps *k*, to the shaft *l*, on which the roller *f* turns, said straps being made adjustable, so that the distance between the hood and the chain-buckets can be suited to the requirements of the work to be performed.

The angle at which the teeth *i*; or the cutting or operating-edge of the bucket *a*, is presented to the bottom, is regulated by adjustment of the straps *m*.

To thrust the plow down against the bottom, the lever *n* is pivoted to *a*, and a chain, *o*, made fast to each

end of the lever, passes around the windlass *p*, so that, by turning the windlass in the direction indicated by the arrow on the drawing, the lever *n* is drawn downward.

The plow *a* is attached to the windlass *q* by the chain *r*, so that the plow and the lower end of frame *d* can be raised and lowered by working windlass *q*, windlass *p* being also worked in conjunction.

In dredging, two moored scows are employed, one before, and the other behind the dredging-machine, and a chain or chains, extending from one scow to the other, pass around a windlass on the dredging-machine, which windlass is strongly and slowly operated by power applied to said windlass, so that the dredging-machine is moved over the place to be dredged.

The proper adjustments of the plow *a*, as to depth, and as to its angle, and its distance from the shaft *l*, being made, the bucket-chain *c* is set in motion, and the dredging-machine is started in motion from the rearward scow toward the forward scow, and thus a kind of ditch is excavated, the material from which is delivered, by the buckets *b*, into a chute, *s*, in a perfectly obvious manner, the chute delivering the material into a scow, which is lashed alongside the dredging-machine.

After the dredging-machine reaches the forward scow, it is, by operation of the propelling-windlass, before mentioned, hauled back to the rearward scow, and, if it is desired to deepen the ditch already made, the plow is thrust down by operation of windlass *p*, and the before-described operation is repeated.

To widen the ditch or channel made, the dredging-machine is set over to the right or left, in any convenient manner, and the dredging-operation is continued, as before described, and when the cut made by the dredging-machine is to be lengthened, then the position of the moored scows is changed, as it must also be if the width of the excavation is considerable.

I claim a dredging or excavating-machine, in which are combined a floating hull, a plow or scoop *a*, and elevating-buckets, all constructed and arranged to operate substantially as set forth.

ALBERT BOSCHKE.
